UNITED STATES PATENT OFFICE

2,421,274

TELEVISION STUDIO CONSTRUCTION

Lawrence Levey, New York, N. Y.

Application December 13, 1944, Serial No. 568,039

3 Claims. (Cl. 95—82)

1

This invention relates generally to a television studio but more specifically to the construction of a studio and apparatus pertaining thereto adapted to facilitate the programming and televising of all types of presentations including commercial spot announcements by maintaining dramatic and pictorial continuity and easing camera movement, framing and focusing.

The main object of the invention resides in the provision of a studio construction and related apparatus to facilitate the televising of productions by rendering movement of television cameras to positions for all types of shots with the least difficulty. This object is important because the average television camera shot lasts from twenty-thirty seconds. For dramatic reasons, many shots are merely flashes on the screen lasting from five to ten seconds. To produce all shots with stop-watch precision, the camera must constantly be moving, framing and focusing. The utilization of cranes for a battery of cameras on the set would cause collision, noise and confusion. It has been estimated that in a television presentation lasting one-half hour no shot should remain on the receiving screen longer than twenty seconds because of the small size thereof, tendency of the eye to shift after prolonged staring at any object and surrounding psychological factors. It becomes therefore necessary to shoot from one hundred twenty to one hundred eighty different shots on the receiving screen, the said number of shots maintaining dramatic and pictorial continuity. For this number of shots it becomes obvious that the battery of television cameras, usually three in the aggregate, move toward and away from the setting for framing and focusing about one hundred twenty to one hundred eighty times during a one-half hour show. For this reason facility of camera movement is of great importance in televising productions.

A further object of the invention resides in the provision of structure for producing montage effects without sacrificing easy movement of the television cameras adjacent thereto.

A further object of the invention resides in the provision of a studio having vertically adjacent master studio floors wherein movable means and other expedients are provided on and between the studio floors to facilitate camera

2

transition, the taking of intermediate and angular camera shots and to provide mobile common and continuous props on and between the floors to facilitate programming.

These objects and other incidental ends and advantages of the invention will hereinafter appear in the progress of the disclosure and as pointed out in the appended claims.

Accompanying this specification are drawings showing preferred forms of the invention wherein:

Figure 1 is a view in perspective partly in section showing a television studio having adjacent master studio floors and means thereon and between for facilitating the televising of productions.

Figure 2 is a longitudinal sectional view of the studio showing features of the studio.

Figure 3 is a transverse sectional view of the studio depicting certain elements shown in Figure 1.

Figure 4 is a fragmentary view partly in section showing the movable mounting means and a floor carriage for a panel.

Figure 5 is a sectional view of Figure 4 along the plane 5—5 thereof.

Figure 6 is a fragmentary view in elevation showing the chain drive and the mounting sockets for the panel elements of the studio.

Figure 7 is a fragmentary view partly in section showing the driving means for fan panels.

The television studio forming the subject matter of the invention herein is preferably comprised of master studio floors vertically arranged. Thus, the studio as shown has side walls 10 and 11, front and rear walls 12 and 13 and vertically adjacent master studio floors 14 and 15.

Each of the floors is provided with mechanically movable mounting means for panels and props whereby they may be shifted and positioned in any predetermined perpendicular, diagonal and aligned relationships. As shown, the means for mechanical movement are in the form of chain drives moving below the level of and in grooves below the floors 14 and/or 15.

The grooves above mentioned are disposed in any predetermined areas and follow any desired geometric patterns on the floors 14 and 15. Thus, there are grooves 16, 17, 18 and 19 and in each one is provided a chain 20 engaging a

sprocket 21 at one end and driven by means such as a motor 22, the chain 20 engaging at the opposite end an idler sprocket 23. A plurality of spaced socket 24 may be carried by the chain 20, the sockets being adapted to engage one or more pegs 25 depending from the lower end of each of the panels or props 26. If a single peg is used for the panels or props, the latter may be rotated so that either face may be shown.

In order to movably support the panels or props 26, a pair of floor carriage units each generally designated by numeral 27 is adapted to support each panel or prop at both side edges, each carriage preferably comprising a pair of rollers 27a spaced beyond each of the floor grooves 16, 17, 18 or 19 and separated on an axle 28. The axle 28 on each side carries a pair of upwardly extending diagonal and converging arms 29 terminating in opposing offset ends 30 engaging sockets 31 on both sides of each of the panels or props. Axle 28 also carries a pair of horizontally disposed and converging arms 32 terminating in opposite offset ends 33 engaging sockets 34 on both sides of each of the panels or props. Between each of the diagonal arms 29 and horizontal arms 32 may be a reinforcing cross piece 35.

The grooves or tracks for the mechanical movements of the panels or props 26 are narrow and permit traversing thereof by the dollies of the television cameras so that shots may be taken at various distances in front of, to the side and at the rear of the panels or props. Said cameras and dollies are not shown in the drawings.

An arrangement for opposite movement of substantially aligned and adjacent panels for introducing and wiping out scenes may be accomplished by the use of parallel and spaced grooves wherein the chains move in opposite directions, and as indicated diagrammatically by the use of parallel grooves in Figure 1. As shown in Figure 7 a fan-shaped opening and closing means is effected by a pair of panels 36 and 37 each of which is mounted within a common groove 38. Panel 37 has a mounting peg 39 which is secured to a hub 40 attached to a pulley wheel 41. Because the center of gravity of panel 37 is outside of hub 40, panel 37 normally would be in the position shown by dotted lines in Figure 7. In order to maintain panel 37 in upright position a cable 42 is passed around pulley 41 and proceeds around an idler 43, the end of the cable 42 proceeding from idler 43 being attached to a similar second pulley for bringing panel 36 into vertical position. Panel 36 is provided with a similar peg 44 mounted in a hub of the second pulley, the latter hub and pulley not being shown in the drawings.

In Figure 1 is shown a panel 45 in the form of a transparent or translucent star area 46 forming the front wall of a compartment 47 wherein aquatic and pyro-technic effects may be incorporated. Openings 48 and 49 may be cut out of adjacent panels 26 to form a round opening 50 therebetween to effectuate any desirable montage effect.

A plurality of suitably arranged and spaced lifts 51 supported on shafts 52 and preferably hydraulically controlled within master cylinders 53 serve as supports for a battery of television cameras, the latter not being shown in the drawings. These lifts penetrate openings 54 in the floor 15 of one of the master studios and enable the cameras to take elevated and depressed horizontal and angular shots between the studio

floors 14 and 15. Openings 54 may have provided seats 54a for automatically operated safety covers, the latter not being shown in the drawings. In addition, there may be one or more apertures 55 in floor 15 whereby an elevated shot may be taken of action on studio floor 14 or a depressed shot may be taken from studio 14 of action taking place on studio floor 15. Aperture 55 also may be provided with a conventional sliding closure such as 56.

A prop such as a stairway 57 is provided between floors 14 and 15 and is preferably swivellably and hingeably supported on floor 15 whereby continuous action between the floors may be televised. Stairway 57 has conventional means of withdrawal to floor 15 as by hinges 58 and may be swivelled about a swivelling element 59. When stairway 57 is in lowered and operative position as shown in Figure 2 a portion of the floor opening 57a may be provided with a conventional safety cover (not shown).

From the foregoing it will be seen that a studio for productions adapted to be televised is provided wherein panels and props are movable along the floor in predetermined directions to effectuate montage effects in relation to action on the studio floors; wherein elevating means operating between and above and below vertically adjacent master studio rooms support television cameras for elevated and depressed angular and horizontal shots in said rooms thereby eliminating the use of cranes; and wherein means are provided between the main studio floors to televise continuous action from one studio to the other. Moreover, the studio described is adapted to co-relate continuous action or dependent action between the vertically adjacent studio rooms.

I wish it understood that minor changes and variations in the construction, location, material and function of the parts may all be resorted to without departing from the spirit of the invention and the scope of the appended claims.

I claim:

1. A studio for productions adapted to be televised comprising a plurality of independent and stationary studio rooms vertically arranged, each of the rooms having a floor provided with areas of spaced and geometrically arranged grooves, members detachably secured in and movable along said grooves in directions to effectuate montage effects, elevating means operating between and above and below vertically adjacent studio rooms to support television cameras for elevated and depressed angular and horizontal shots for continuous action in said rooms, and a prop member joining said rooms whereby the cameras are enabled to televise continuous action from one studio room to the other.

2. In a studio for productions adapted to be televised including a plurality of independent and stationary studio rooms vertically arranged, the upper of the rooms having a floor aperture for elevated and depressed angular camera shots with respect to the lower and upper rooms respectively, elevating means operating between and above and below the rooms to support television cameras for elevated and depressed angular and horizontal shots for continuous action in said rooms, and a prop member joining said rooms whereby the cameras are enabled to televise continuous action from one room to the other.

3. In a studio for productions adapted to be televised including a plurality of independent and stationary studio rooms vertically arranged, elevating means operating between and above and

below vertically adjacent studio rooms to support television cameras for elevated and depressed angular and horizontal shots in said rooms, and an adjustably secured prop member capable of joining said rooms whereby the cameras are enabled to televise continuous action from one room to the other.
